CLAIM

I claim the ornamental design for a toy sports car, as shown and described.

DESCRIPTION

FIG. 1 is a front perspective view of a toy sports car. FIG. 2 is an alternate front perspective view of the toy sports car of FIG. 1.

FIG. 3 is a side view of the right side of the toy sports car of FIG. 1.

FIG. 4 is a side view of the left side of the toy sports car of FIG. 1.

FIG. 5 is a top view of the toy sports car of FIG. 1.

FIG. 6 is a bottom view of the toy sports car of FIG. 1.

FIG. 7 is a front view of the toy sports car of FIG. 1; and, FIG. 8 is back view of the toy sports car of FIG. 1.

The broken line shown represents portions of a toy sports car and forms no part of the claimed design.
